UNITED STATES PATENT OFFICE.

HENRY W. SIMMS, OF BAY CITY, MICHIGAN.

WRENCH.

No. 855,483.

Specification of Letters Patent.

Patented June 4, 1907.

Application filed June 6, 1906. Serial No. 320,406.

To all whom it may concern:

Be it known that I, HENRY W. SIMMS, a citizen of the United States, residing at Bay City, in the county of Bay and State of Michigan, have invented certain new and useful Improvements in Wrenches; and I do hereby declare the following to be a full, clear, and exact description of the invention, such as will enable others skilled in the art to 5 which it appertains to make and use the same.

My invention relates to an improvement in wrenches and more particularly that class of nut wrenches provided with a rigid jaw 15 and a slideable jaw movable toward and from the rigid jaw and instantly locked at any point of its travel.

One object of the invention is the provision of an adjustment which is much more 20 rapid and sure than the ordinary screw adjustment.

Another object is the provision of a one-hand adjustment whereby the slideable jaw can be operated by the same hand which 25 grasps the wrench.

A still further object is the provision of a movable jaw which is releasable from the stock of the wrench so that it can be quickly 30 adjusted to accommodate nuts of varying size, the jaw being automatically locked to the stock when the desired adjustment is obtained.

A further object is the provision of a neat, simple and highly efficient wrench of this 35 character which can be easily manufactured and placed on the market at a low figure.

To these and other ends, therefore, my invention consists in certain novel features and 40 combinations of parts together with their equivalents, such as will be more fully described hereinafter and particularly pointed out in the claims.

In the accompanying drawings illustrating 45 one embodiment of my invention, Figure 1 is a side view of a wrench, Fig. 2 is a similar view, parts being removed to better disclose the construction, Fig. 3 is a detail side view of the pawl, and Fig. 4 is an end view of the movable jaw.

50 A indicates the usual handle or stock provided with a stationary jaw (1), the stock being toothed as at (3), the teeth inclined toward the stationary jaw (1), that end of the handle opposite the jaw being preferably 55 reduced as at (4) to permit the slideable jaw to extend thereover and take into the teeth (3).

5 indicates a strap inclosing and sliding upon the handle or stock, the movable jaw (6) being rigidly secured between the ends of the strap, so that the handle is confined between the strap and the rear face of the movable jaw. The front face of the movable jaw is cut away to receive the locking pawl (7), the ends of the strap projecting past the recessed portion of the jaw so as to embrace 60 a portion of the pawl, whereby to guide the same in its movement. The tail (8) of the pawl projects below the strap and is toothed to mesh with the teeth (3) of the handle.

The head (9) of the pawl projects beyond 70 the strap and is rounded so as to be received in a similarly shaped bearing or socket formed in the movable jaw, said bearing terminating in a stop (10) against which the neck (11) of the pawl contacts, whereby the 75 outward movement of the pawl is limited, and intermediate the socket bearing and the cutaway portion of the jaw is located a shoulder (12) against which one end of a spring (13) bears, said spring located between the 80 pawl and the cut-away portion of the jaw, the opposite end of the spring being loosely received in a kerf (13^a) in the tail of the pawl.

In order to retain the pawl in assembled 85 position yieldingly in contact with the jaw, I provide a pin (14) which passes through the projecting ends of the strap and between the pawl and spring, and by reason of the resiliency of the spring the toothed tail of the 90 pawl is yieldingly held in mesh with the teeth (3) of the handle, the head of the pawl being pivotally received in the socket formed in the jaw.

As one means for rocking the pawl to cause 95 a disengagement of the tail and the teeth (3), I provide an inclined lever (15) pivotally secured to the pawl at a convenient point intermediate its ends, such lever comprising an approximately U-shaped body portion from 100 which preferably projects a thumb piece (16). The legs of the lever are preferably, though not necessarily squared at their free ends and normally engage the ends of the strap, the pivot pin (17) passing through the legs near 105 their lower ends. Pressure upon the thumb piece (16) will rock the lever causing the rear corners of the legs to press against the stationary strap whereby the pawl is rocked or lifted against the tension of the spring (13), 110 so that its toothed tail is disengaged from the teeth (3) whereby to permit the jaw,

strap and pawl to be moved in either direction to accommodate work of various sizes.

Owing to the inclination of the teeth on the handle and on the pawl, the movable jaw is freely movable toward the stationary jaw, but cannot be moved away from the jaw except by releasing the pawl from the handle by operating the thumb lever. It will be further noted that the pawl assumes an inclined position relative to the movable jaw and the handle so that when the wrench is in use the pressure brought to bear against the outer end of the movable jaw will be sustained by the pawl which serves as a brace, such pressure being transmitted through the pawl directly to the handle and the greater such pressure, the more tenacious will the teeth of the pawl and handle engage each other, the inclination of such tooth being in the line of pressure exerted upon the movable jaw.

When it is desired to remove the pawl from the jaw, all that is necessary is to grasp the tail of the pawl firmly and raise it from the handle and against the tension of the spring (13) until the pawl has cleared the projecting ends of the straps, whereupon it may be slid or moved sidewise to release the head of the pawl from the socket, the end of the spring being loosely received in a kerf in the tail of the pawl and hence opposing no resistance save perhaps frictional to the sidewise movement of the pawl.

It would be unnecessary to remove the pawl except in case of the breakage of the spring or other parts, or in case some foreign material happened to work into the space between the pawl and jaw.

From the foregoing, therefore, it is evident that I have devised a simple yet neat and strong tool of the character set forth, which can be used more easily and adjusted more quickly than the ordinary form of screw wrench, besides affording a brace for the strain brought to bear on the outer end of the movable jaw and providing means for instantly locking the jaw to and unlocking it from the handle to admit of its adjustment to the work.

Having thus fully disclosed my invention, what I claim as new is—

1. A wrench comprising a handle and stationary jaw, teeth on the handle, a strap slidably mounted on the handle, a jaw fixed to the sliding strap, and closing the strap, the jaw being cut away and having a socket formed near its outer end, a pawl received between the projecting ends of the strap, the pawl superposed upon the jaw, one end of the pawl received in the socket, a stop carried by the jaw adjacent the socket to limit movement of the pawl in one direction, teeth on the opposite end of the pawl adapted to mesh with the teeth on the handle, a lever pivotally secured to the pawl and bearing on

the ends of the strap, to release the teeth of the pawl from the teeth of the handle, and a spring, carried by the pawl and engaging the jaw to normally retain the teeth of the pawl in engagement with the teeth of the handle. 70

2. A wrench comprising a toothed handle, a movable jaw slidably mounted on the handle, and having a socket formed therein, a pawl, one end of which is pivotally received in the socket, teeth on the opposite end of the pawl adapted to mesh with the teeth on the handle, a spring for yieldingly retaining the teeth in mesh, the pawl lying in alignment with the pressure brought on the outer end of the movable jaw, and bracing the latter and a lever pivotally secured to the pawl and having a rocking engagement with the jaw for releasing the teeth of the pawl from the teeth of the handle against the tension of the spring. 80

3. In a wrench, the combination with a toothed stock, of a slidable jaw mounted on the stock, a pawl, one end of which pivotally engages the movable jaw, teeth on the opposite end of the pawl meshing with the teeth on the handle, means for yieldingly retaining the teeth in mesh and a lever pivotally secured to the pawl and having a rocking engagement with the jaw for raising the toothed end of the pawl. 90

4. A wrench comprising a toothed stock and a fixed jaw, a U-shaped strap slidably inclosing the stock, a jaw cut away throughout a portion of its length and fixedly carried by the strap, the ends of the strap projecting beyond the cut away portion of the jaw, a shoulder formed on the cut away portion of the jaw, a pawl received between the ends of the strap and superposed upon the jaw, one end of the pawl pivotally engaging the jaw, teeth on the opposite end of the pawl meshing with the teeth on the stock, the pawl having a kerf formed therein, a spring, one end of which is seated in the kerf, the opposite end engaging the shoulder on the jaw and a lever pivoted to the pawl, the lever bearing against the end of the strap to raise the toothed end of the pawl. 100

5. A wrench comprising a toothed stock, a jaw movable thereon, a squared face on the jaw a pawl toothed at one end, the opposite end of the pawl being journaled in the jaw, and a releasing lever pivoted to the pawl adjacent the squared face of the jaw, one end of the lever resting on the jaw and having a squared face corresponding with that of the jaw when the pawl is in locked position relative to the stock. 110

6. A wrench comprising a toothed stock a jaw slidable on the stock, a pawl, one end of which is pivotally connected to the jaw, teeth on the opposite end of the pawl meshing with the teeth on the stock, a pivot carried by the jaw and engaging the pawl intermediate its ends, a spring passing under 120

the pivot and in contact with the jaw, the opposite ends of the spring engaging the pawl on opposite sides of the pivot, and a lever for moving the pawl on its pivot out of engagement with the teeth on the stock.

7. A wrench comprising a toothed stock and a movable jaw slideable on the stock, a pawl, one end of which is pivotally connected to the movable jaw, teeth on the pawl engaging the teeth on the stock and a lever

pivotally secured to the pawl, one end of the lever having a rocking contact with and bearing against the jaw to release the teeth of the pawl from the teeth of the handle.

In testimony whereof, I affix my signature ¹⁵ in presence of two witnesses.
